UNITED STATES PATENT OFFICE

GEORGE GODDU, OF WINCHESTER, MASSACHUSETTS, ASSIGNOR TO UNITED SHOE MANUFACTURING CORPORATION, OF PATERSON, NEW JERSEY, A CORPORATION OF NEW JERSEY

METHOD OF ANCHORING STAPLES AND PRODUCT THEREOF

Original application filed August 16, 1926, Serial No. 129,425. Divided and this application filed January 23, 1929. Serial No. 334,525.

This invention relates to the anchoring of staples in work into which they are driven, and in different aspects provides a novel method and a novel product, this application being a division of a copending application Serial No. 129,425, filed on August 16, 1926.

In Letters Patent No. 1,742,502, granted upon an earlier application of mine on January 7, 1930, I disclosed and claimed a novel method of anchoring staples by deflecting or curving the legs of each staple laterally of the cross-bar, i. e., transversely of the plane determined by the legs and the cross-bar before the bending of the legs takes place, through force applied at the same side of the work from which the staple is driven, thus causing the legs to follow curved paths in the work such as to anchor them without the need of clinching them on any surface of the work. As applied, for example, to the manufacture of shoes of that type in which the outsole is fastened to the insole by stitches that penetrate through both the outsole and the insole, frequently termed through-and-through stitches, that method is especially advantageous in the fastening of the upper in lasted position on the outer or bottom face of the insole along the sides of the shoe, since by its use the upper may be fastened by staples so anchored as to avoid the presence of clinched metallic fastenings on the inner face of the insole in the locations of the side-lasting tacks that have been commonly used in making shoes of that type.

The present invention provides a novel method affording increased insurance that a staple anchored without clinching, for example in the manner above described, will successfully resist all strains tending to withdraw it from the work, either as applied to the fastening of uppers to soles or insoles or in more general relations. In accordance with the novel practice herein illustrated the legs of the staple, while being driven and curved laterally of the cross-bar, are also relatively deflected lengthwise of the cross-bar. This is conveniently accomplished, as herein shown, by the use of suitable guiding grooves provided in the deflecting mem-

ber which acts to curve the legs laterally of the cross-bar, so that the legs are relatively deflected by the grooves lengthwise of the cross-bar while they are being driven and curved. The staple is thus anchored in the work by the combined effect of the curvature of the legs laterally of the cross-bar and their relative deflection lengthwise of the cross-bar. As herein illustrated both legs are thus deflected and the deflection is such as to spread the legs apart, but the invention is not limited to that particular manner of treatment.

In addition to its novel method aspects, the invention further presents novelty in a shoe provided with staples anchored as described for fastening the upper in lasted relation to the sole or insole, and in a still more general aspect novelty also in work comprising a plurality of layers of material fastened together by such a staple or staples.

The invention will now be more particularly described by reference to the accompanying drawings and thereafter pointed out in the claims. In its method aspects the invention is herein illustrated by reference to mechanism adapted for use in practising the method in the lasting of shoes, that mechanism being more fully shown and described in the copending application of which this application is a division.

In the drawings, Fig. 1 is a sectional view of a portion of the mechanism above referred to and of a shoe under treatment, illustrating especially how the legs of the staple are curved laterally of the cross-bar;

Fig. 2 is a view on an enlarged scale of the deflecting member which acts to curve the legs of the staple, showing the grooves for deflecting the legs lengthwise of the cross-bar;

Fig. 3 is a view on an enlarged scale illustrating how the staple legs diverge from each other after the staple has been driven, one of the legs being shown in dotted lines in the work and the latter being broken away to show the other leg in full; and

Fig. 4 is a sectional view showing a portion of a completed shoe of the through-and-

through sewed type having its upper materials secured to the insole in lasted position by staples anchored in the manner provided by this invention.

5 As more fully disclosed in the above-mentioned application of which this is a division, the mechanism shown in Fig. 1 comprises an edge gage 10 and a bottom rest 12 in engagement with which a shoe in the hands of an operator is presented as illustrated, the shoe being moved by the operator to permit the lasting of different portions thereof successively. In each lasting position of the shoe the upper materials (hereinafter frequently referred to inclusively as the upper), comprising as shown the upper leather *a* and the lining *b*, are pulled by a gripper (not shown) and are then laid inwardly over the insole *c* by mechanism including a carrier 14 which is moved in a direction inclined to the plane of the insole, the carrier having thereon a staple-guiding nozzle a portion of which is shown at 16. The staple for fastening the upper to the insole is preferably formed with legs that are straight before the staple is driven, the legs and the cross-bar then lying in the same plane, as in the common form of staple, and the staple is driven from the nozzle 16 by a 10 driver 18 moving in a direction inclined to the bottom face of the insole. As the staple is thus driven its legs *d* are engaged by a deflecting member 20 mounted on the carrier 14 with its lower end in a position opposite to the end of the staple-guiding passage in the nozzle 16. The staple legs are thus engaged by the deflecting member 20 at the same side of the work from which the staple is driven, i. e., without the presence 15 of any portion of the work between the deflecting member and the staple nozzle, and by the action of the deflecting member different portions of the legs are curved successively in the driving operation in directions laterally of the cross-bar *e* and both at the same side of the cross-bar before the different respective portions enter the work. As herein illustrated, the staple is driven in a direction inclined inwardly from the edge 20 of the insole with the cross-bar substantially parallel to the insole edge, and the legs are so deflected that they enter the shoe in directions approximately perpendicular to the bottom face of the insole and then follow curved paths leading back toward that surface of the work at which they entered, or in directions substantially opposite to that of the drive, so that they are anchored in the body or intact substance of the insole 25 with their ends directed reversely toward the outer or bottom face of the insole. The legs are preferably curved, as illustrated, in such degree as not to penetrate the inner face of the insole. Their ends may or may not emerge from the bottom face of the in-

sole, since, if they do so emerge, they will be covered by the outsole; and there is, in any event, no danger that the ends of the legs will work up into the interior of the shoe in the wear of the shoe. It will be further noted that, with the staple driven in a direction inclined inwardly from the edge of the insole, as illustrated, the legs are curved outwardly toward the edge of the insole. As thus far described the manner of anchoring the staple in the work is substantially such as disclosed in the above-mentioned Letters Patent.

70 In order to increase the holding power of the legs of the staple in the work, and thus to afford further insurance that the staple will not be loosened in the work by the strain thereon, this invention provides for effecting a relative deflection of the legs lengthwise of the cross-bar. This may be conveniently accomplished, as shown, by the use of non-parallel guideways or grooves 22 (Fig. 2) in the staple-engaging face of the deflecting member 20 to receive and guide the legs of the staple as they are being driven and curved 75 in the manner hereinbefore described. These grooves, as herein illustrated, are so arranged that each of the legs is deflected in a direction away from the other leg, the legs thus being spread apart as they are driven so that they 80 diverge from each other in the work. The shape of the staple after it has been driven is illustrated in Fig. 3. While I believe it to be preferable thus to deflect both legs in such manner as to spread them apart, the invention 85 is not limited to this particular manner of treatment. The extent of the deflection also may be varied as desired by suitable arrangement of the grooves 22.

90 Fig. 4 shows a portion of a completed shoe 100 of the type illustrated, i. e., a shoe in which the outsole *f* is secured to the insole *c* by stitches *g* that pass through both the outsole and the insole, frequently termed through-and-through stitches. It will be observed that 105 the staples, driven and anchored as hereinbefore described in the side-lasting of the shoe, remain as permanent parts of the shoe. A shoe thus made, while free from metallic fastenings clinched on the inner face of the insole 110 along the sides of the shoe, like that disclosed in the above-mentioned Letters Patent, is further improved by reason of the increased insurance against loss of shape in the interval 115 between the lasting of the shoe and the fastening of the outsole to the shoe due to the security of the connection between the upper and the insole afforded by the relative deflection of the legs of each lasting staple lengthwise of the cross-bar in addition to their 120 curvature laterally of the cross-bar.

125 While the invention is herein illustrated and described with particular reference to the fastening of uppers to insoles in the manufacture of shoes of the through-and-through 130

sewed type, it is considered that in various aspects the method disclosed may be utilized advantageously for fastening uppers in the manufacture of shoes of other types, and the term "sole" is accordingly used in many of the claims in a comprehensive sense to include both the insole of certain types of shoes and also that part which in shoes of other types may be the outsole or the only sole with which the shoe is provided. Furthermore, it is considered that in a more general aspect the invention is not limited in utility to the fastening of uppers nor, in fact, to shoe manufacture.

Having described the invention, what I claim as new and desire to secure by Letters Patent of the United States is:—

1. That improvement in methods of anchoring a staple as it is driven into a piece of work which consists in applying to the legs of the staple in the driving operation, at the same side of the work from which the staple is driven, forces so directed as to deflect the legs in curved paths laterally of the cross-bar of the staple and also to effect a relative deflection of the legs lengthwise of the cross-bar.

2. That improvement in methods of anchoring a staple as it is driven into a piece of work which consists in curving the legs of the staple in the driving operation throughout substantially their whole length laterally of the cross-bar and effecting simultaneously a relative deflection of the legs lengthwise of the cross-bar.

3. That improvement in methods of anchoring a staple as it is driven into a piece of work which consists in curving the legs of the staple in the driving operation throughout substantially their whole length laterally of the cross-bar and both at the same side of the cross-bar and effecting simultaneously a relative deflection of the legs lengthwise of the cross-bar.

4. That improvement in methods of anchoring a staple as it is driven into a piece of work which consists in applying to the legs of the staple in the driving operation, at the same side of the work from which the staple is driven, forces acting to curve the legs laterally of the cross-bar in paths leading back toward that surface of the work at which they entered while also effecting a relative deflection of the legs lengthwise of the cross-bar.

5. That improvement in methods of anchoring a staple as it is driven into a piece of work which consists in applying to the legs of the staple in the driving operation, at the same side of the work from which the staple is driven, forces so directed as to cause the legs to diverge from each other in the work.

6. That improvement in methods of anchoring a staple as it is driven into a piece of work which consists in applying to the legs

of the staple in the driving operation, at the same side of the work from which the staple is driven, forces so directed as to curve the legs laterally of the cross-bar of the staple and also to spread them apart.

7. That improvement in methods of driving and anchoring staples which consists in applying driving force to a staple in a direction inclined to that surface of the work into which the staple is driven, and by engaging the legs of the staple in the driving operation at the same side of the work from which the staple is driven deflecting them laterally of the cross-bar, both at the same side of the cross-bar, in such manner as to cause their ends to follow in the work curved paths leading back in directions substantially opposite to that of the drive and diverging from each other.

8. That improvement in methods of driving and anchoring staples which consists in applying driving force to a staple in a direction inclined to that surface of the work into which the staple is driven, and by engaging the legs of the staple in the driving operation at the same side of the work from which the staple is driven deflecting them laterally of the cross-bar in curved paths leading back in directions substantially opposite to that of the drive while also effecting a relative deflection of the legs lengthwise of the cross-bar.

9. That improvement in methods of fastening an upper in lasted relation to a sole which consists in driving a staple through the upper and the outer or bottom face of the sole, and in the driving of the staple curving its legs substantially throughout their length laterally of the cross-bar, while also effecting a relative deflection of the legs lengthwise of the cross-bar, in such manner as to anchor them in the intact substance of the sole without penetrating the inner face of the sole.

10. That improvement in methods of fastening an upper in lasted relation to a sole which consists in driving a staple through the upper and into the sole, and in the driving of the staple curving its legs substantially throughout their length laterally of the cross-bar, while also spreading them apart, to anchor them in the sole.

11. That improvement in methods of fastening an upper in lasted relation to a sole which consists in driving a staple through the upper and the adjacent face of the sole, and in the driving operation curving the legs of the staple laterally of the cross-bar from the points where they enter the sole in such degree as to direct their ends reversely toward said face, while also effecting a relative deflection of the legs lengthwise of the cross-bar, to anchor them in the sole.

12. That improvement in methods of fastening an upper in lasted relation to a sole which consists in driving a staple through the upper and into the sole, and by engaging

- the legs of the staple in the driving operation at the same side of the work from which the staple is driven deflecting them in curved paths laterally of the cross-bar of the staple and also deflecting them relatively to each other lengthwise of the cross-bar to anchor them in the sole.
13. That improvement in methods of fastening an upper in lasted relation to a sole which consists in driving a staple in a direction inclined to the plane of the sole, and by engagement with the legs of the staple in the driving operation bending different portions of them successively laterally of the cross-bar and both at the same side of the cross-bar, before the different respective portions enter the shoe materials, to cause them to take curved paths in said materials; while also effecting by said engagement a relative deflection of the legs lengthwise of the cross-bar, to anchor the staple in the sole.
14. That improvement in methods of fastening an upper to a sole which consists in driving a staple through the upper and into the sole in a direction transverse to the plane of the sole, and anchoring the staple in the intact substance of the sole by bending its legs both laterally and lengthwise of the cross-bar without penetrating that face of the sole which is on the side opposite to that from which the staple is driven.
15. That improvement in methods of fastening an upper in lasted relation to a sole which consists in driving a staple through the upper and into the sole by force applied in a direction inclined inwardly from the edge of the sole with the cross-bar of the staple extending substantially parallel to the edge of the sole, and by engaging the legs of the staple in the driving operation at the same side of the work from which the staple is driven curving the legs laterally of the cross-bar of the staple outwardly toward the edge of the sole and also deflecting them relatively to each other lengthwise of the cross-bar to anchor them in the sole.
16. That improvement in methods of fastening an upper to a sole which consists in driving a staple through the upper and into the sole, and by engaging the legs of the staple in the driving operation at the same side of the work from which the staple is driven spreading them apart to anchor them in the sole.
17. That improvement in methods of fastening an upper to a sole which consists in driving a staple through the upper and into the sole, and by engaging the legs of the staple in the driving operation at the same side of the work from which the staple is driven curving them laterally of the cross-bar of the staple, both at the same side of the cross-bar, and also spreading them apart, to anchor them in the sole.
18. A shoe having as a permanent part thereof staples securing the upper in lasted relation to the sole, the legs of each staple being curved laterally of the cross-bar substantially throughout their length and being different distances apart at different portions of their length.
19. A shoe having as a permanent part thereof staples securing the upper in lasted relation to the sole, the legs of each staple being curved laterally of the cross-bar substantially throughout their length and also diverging from each other lengthwise of the cross-bar.
20. A shoe of the through-and-through sewed type having as a permanent part thereof staples securing the upper in lasted relation to the outer or bottom face of the insole, the legs of each staple being curved laterally of the cross-bar at the same side thereof substantially throughout their lengths in paths of such radius as not to penetrate the inner face of the insole and being also different distances apart at different portions of their length.
21. A shoe of the through-and-through sewed type having as a permanent part thereof staples securing the upper in lasted relation to the outer or bottom face of the insole, the legs of each staple being curved laterally of the cross-bar at the same side thereof substantially throughout their length in such degree that their ends are directed reversely toward the outsole and being also different distances apart at different portions of their length.
22. The combination with a plurality of layers of material, of a staple securing said layers together, said staple having its legs curved laterally of the cross-bar substantially throughout their length and different distances apart at different portions of their length.
23. The combination with a plurality of layers of material, of a staple securing said layers together, said staple having its legs curved laterally of the cross-bar substantially throughout their length and also diverging from each other lengthwise of the cross-bar.
24. The combination with a plurality of layers of material, of a staple securing said layers together, said staple having its legs curved laterally of the cross-bar at the same side thereof substantially throughout their length and different distances apart at different portions of their length.
25. The combination with a plurality of layers of material, of a staple securing said layers together, said staple having its legs curved laterally of the cross-bar from the points where they entered the material in such degree that their ends are directed reversely toward that surface of the material at which they entered, the legs being also

different distances apart at different portions of their length.

26. The combination with a plurality of layers of material, of a staple securing said layers together, said staple having its legs curved laterally of the cross-bar at the same side thereof substantially throughout their length in such degree that their ends are directed reversely toward that surface of the material at which they entered without penetrating entirely through the material, the legs also diverging from each other lengthwise of the cross-bar.

10 In testimony whereof I have signed my name to this specification.
